WOVEN CURTAIN FABRIC
Harry Horowitz, 499 7th Ave., Summit, N.J.
Filed May 6, 1959, Ser. No. 811,391
5 Claims. (Cl. 139—384)

The present invention relates to a novel drapery fabric and it particularly relates to a method of making such drapery fabric.

It is among the objects of the present invention to make a novel drapery fabric which can be readily woven by standard procedures in a loom and which after weaving may be readily converted into a drapery fabric without additional processing.

It is a further object of the present invention to make a drapery fabric which may be directly woven upon the loom and which by simple manipulation may be converted into an attractive drape or curtain.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory to weave a drapery fabric so that included with the normal weft and warp strands there will be an additional relatively heavy readily adjustable or slideable warp strands or group of warp strands which will permit the fabric to be drawn up into attractive drapery appearance or ruffled appearance permitting it to be immediately utilized without further mechanical processing or sewing or stitching as a curtain or drape.

The relatively heavy warp strands which are responsible for this procedure should have a diameter or thickness preferably about two to three times and sometimes up to four or five times the diameter of the other weft or warp strands.

Their surface should be relatively smooth so that they may slide through the overlooping or engaging warp and weft strands but at the same time they should maintain their adjusted position after the fabric has once been drawn up so that it will have its final curtained or ruffled appearance.

With the foregoing and other objects in view, the invention consists of the novel construction, combination and arrangement of parts as hereinafter will be more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

FIG. 1 is a side diagrammatic view showing the manner of weaving the fabric of the present invention upon a loom.

FIG. 2 is a fragmentary plan view showing the construction of the fabric after it has been woven.

FIG. 3 is a transverse sectional view upon the line 3—3 of FIG. 2.

FIG. 4 is a fragmentary plan view upon enlarged scale as compared to FIGS. 2 and 3 of the portion of the fabric of FIG. 2.

FIG. 5 is a fragmentary top perspective view showing a portion of the fabric upon a greatly enlarged scale as compared to FIGS. 2, 3 and 4.

FIG. 6 is a diagrammatical elevational view showing the manner in which the fabric has been gathered to-

2

gether by the use of the extra warp strands woven thereinto.

FIG. 7 is a transverse sectional view upon the line 7—7 of FIG. 6.

FIG. 8 is an elevational view of the portion of the fabric of FIG. 6 showing the fabric construction.

FIG. 9 is a fragmentary diagrammatic transverse sectional view of a fabric construction upon enlarged scale showing the doubling of the heavy pull strand S with a warp strand.

FIG. 10 is a fragmentary diagrammatic transverse sectional view of a fabric construction upon enlarged scale showing the tripling of the heavy pull strand S with a warp strand.

Referring to FIGS. 2 to 8, the fabric may be a woven fabric with a taffeta weave such as is shown in FIG. 5 with the warp strands 51 and the filler or weft strands 50.

The important feature of the present invention is that there is woven into the fabric a relatively heavy strand S which is frictionally retained in adjusted position between the warp strands 51 and by the filler or weft strands 50 without being locked in position, as is true of the usual manner of the weft and warp strands.

This condition continues even if the fabric be finished and even if the fabric be subsequently sized.

Desirably the strand S, two or three of which are used parallel to one another, as shown in FIGS. 2 and 6, has a dimension or thickness of about two to three times the thickness of the weft and warp strands 50 and 51 and it has a substantially smooth surface which might be slightly abraded as by frictional contact or by sand blasting so that it will hold in adjusted position as shown in FIGS. 6, 7 and 8.

An important feature of the present invention is the fact that such strand S is of extra weight or denier and also has a slightly roughened surface which nevertheless will slip through the closely knitted filler strands 50.

In weaving this fabric the warp strands E come off the usual shed and are separated by means of the reciprocating vertically positioned heddles D.

These heddles will form the alternating weft strands into the sheds 23 and 24.

The extra strands S are fed from independent feed roller 17 over the guide rollers 19 on the shafts 18 into selected heddles to form the strands 25 which are woven into the fabric by the filler placed therein by the shuttles L.

The loom is driven from the shaft 75 provided with the fly wheel 20 and the follower arm 22 and the cam 21.

The lay G will reciprocate backwardly and forwardly upon the shaft 26 and the reed M will separate the warp strands 51 and will beat up the strands to the fell position.

The woven fabric will appear as shown in FIG. 2 with groups of relatively heavy slideable or adjustable warp strands S in the fabric R which are held in position in the manner diagrammatically shown in FIG. 5 but which when drawn up will gather the fabric so that it may be used as an attractive drape or curtain of the Viennese type.

The strands S as shown in FIGS. 4 and 8 alternate so that only one or two groups of filler or weft strands are on each side thereof but for greater clarity, a larger or smaller number are shown thereon.

Although not restricted thereto, it has been found satisfactory to double with the pulling or slipping warp S, one or two normal size warps 51 so as to enable the heavy warp S more readily to be drawn through the fabric to achieve the drape effect as shown in FIGS. 6 and 7.

This may be accomplished either by feeding the warp

end S with one or more normal warp ends 51 through the same heddle eye.

However, it is preferably accomplished by so setting the dobby mechanism so that the pulling strand S will be positioned alongside a relatively thin diameter strand 51.

The strand S may be of high tenacity rayon of 800 to 1500 denier and it may consist of two ends having an organzine twist. The normal warp and filling strands may be of 75 denier acetate.

Generally the preferred weave is composed of warp and filler strands of relatively small diameter having a denier of 75 to 100 together with spaced relatively heavy warp strands having a denier of 750 to 1500.

Desirably the weave is a taffeta weave with one end up and one end down and with the heavy strand S always being included in the same filler loop with one or more of the thin strands 51.

If desired, this heavy strand S may be shifted back and forth so that it will be looped together with the thin warp strand on one side and then with the thin warp strand on the other side and although the main strand S is desirably of doubled high tenacity rayon, it may also consist of doubled mixed strands of nylon and rayon or of double strands of nylon.

In the preferred form, the strands S consist of non-stretchable rayon or nylon, whereas the small diameter filler and warp strands 50 and 51 of 50 to 75 denier with either bright or dull surface and permit ready slippage of the heavy strands S.

In FIG. 9 is shown the construction in which the taffeta weave represented by the over and under filler strands 61 and 62 forms a series of pockets in which there is normally only one warp strand 60.

However in the pocket 63 which receives the heavy warp strand S, there will also be doubled with the heavy strand S a single warp strand 64. This aids in the pulling and gathering of the fabric in the manner shown in FIGS. 6 and 7.

In the transverse section as shown in FIG. 10, the filler strands 70 and 71 in combination with the normal warp strands 72 may form a standard woven fabric except for the pockets 75 which receive the heavy strand S for gathering purposes.

The heavy strand S may be tripled with the normal warp strands 73 and 74 so that the heavy strand S may be most readily drawn up in respect to the fabric to give the gathered effect.

While I have shown the invention in but one form, it will be obvious to those skilled in the art, that it is not so limited, but is susceptible of various changes and modifications, without departing from the spirit thereof, and I desire therefore that only such limitations shall be placed thereupon as are imposed by the prior art or as are specifically set forth in the appended claims.

Having now particularly described and ascertained the

nature of the invention, and in what manner the same is to be performed, what is claimed is:

1. A woven curtain fabric comprised of a weave having interwoven warp and filler strands of relatively small diameter and spaced relatively heavy warp strands, to be drawn up in said weave to form a ruffled drape, said heavy warp strands consisting of two ends with an organzine twist combined together and having an abraded surface so that it will hold itself frictionally in adjusted position.

2. A woven curtain fabric comprised of a weave having interwoven warp and filler strands of relatively small diameter and spaced relatively heavy warp strands, to be drawn up in said weave to form a ruffled drape, said warp and filler strands being of cellulose acetate and said heavy warp strand being of rayon, said heavy warp strands consisting of two ends with an organzine twist combined together and having an abraded surface so that it will hold itself frictionally in adjusted position.

3. A woven curtain fabric comprised of a weave having interwoven warp and filler strands of relatively small diameter and spaced relatively heavy warp strands, to be drawn up in said weave to form a ruffled drape, said weave being composed of strands having a denier of 75 to 100 while said heavy strands have a denier of 750

25 to 1500, said heavy warp strands consisting of two ends with an organzine twist combined together and having an abraded surface so that it will hold itself frictionally in adjusted position.

30 4. A woven curtain fabric comprised of a weave having interwoven warp and filler strands of relatively small diameter and spaced relatively heavy warp strands, to be drawn up in said weave to form a ruffled drape, said heavy strands being doubled in the same filler loops with 35 the small diameter warp strands, said heavy warp strands consisting of two ends with an organzine twist combined together and having an abraded surface so that it will hold itself frictionally in adjusted position.

35 5. A taffeta woven ruffled curtain fabric composed of a taffeta weave having interwoven warp and filler cellulose acetate strands of relatively small diameter of 75 denier and spaced relatively heavy rayon strands of a high tenacity, two end organzine twist rayon of 800 to 1500 denier, said heavy strands in each filler loop being 40 accompanied and positioned in contacting relationship with at least one small diameter warp strand having a smooth slippable surface and said heavy rayon strands having a slightly roughened friction grip surface.
